US00D831666S

(12) **United States Design Patent** (10) **Patent No.:** **US D831,666 S**
(45) **Date of Patent:** **** Oct. 23, 2018**

(54) **PORTABLE DEVICE HOLDER**

(71) Applicant: **Kenu, Inc.**, San Francisco, CA (US)

(72) Inventors: **David E. Yao**, San Francisco, CA (US);
Leonard John Duran, Mill Valley, CA (US); **Gregory D. Caneer**, Oakland, CA (US); **Kenneth Y. Minn**, San Francisco, CA (US)

(73) Assignee: **KENU, INC.**, San Francisco, CA (US)

(**) Term: **15 Years**

(21) Appl. No.: **29/617,064**

(22) Filed: **Sep. 11, 2017**

(51) LOC (11) Cl. **08-07**

(52) U.S. Cl.

USPC **D14/447**

(58) **Field of Classification Search**

USPC D14/447, 432, 434, 439, 440, 451, 452, D14/457, 239; D8/363, 373, 380;

(57) **CLAIM**

The ornamental design for a portable device holder, as shown and described.

DESCRIPTION

FIG. 1 is a rear perspective view of a portable device holder; FIG. 2 is a front perspective view of the portable device holder;

FIG. 3 is a front elevational view of the portable device holder;

FIG. 4 is a rear elevational view of the portable device holder;

FIG. 5 is a top plan view of the portable device holder;

FIG. 6 is a bottom plan view of the portable device holder;

FIG. 7 is a right elevational view of the portable device holder; and,

FIG. 8 is a left elevational view of the portable device holder.

1 Claim, 4 Drawing Sheets
